UNITED STATES PATENT OFFICE.

JOHN S. SMALL, OF NEW YORK, N. Y.

FILE.

Application filed October 5, 1921. Serial No. 505,643.

This invention relates to files and is more particularly though not exclusively concerned with card indexes of the class in which the cards are arranged with their identification-receiving margins in overlapping relationship. The invention will be best understood by reference to the following description when taken in connection with the accompanying drawings of one 5 illustrative embodiment thereof, while its scope will be more particularly pointed out in the appended claims.

In the drawings:

Fig. 1 is a front elevation of a portion of 15 a card index exemplifying the invention;

Fig. 2 is a sectional view on line 2—2 of Fig. 1;

Fig. 3 is a detail front elevation of one of the card supporting bars;

20 Fig. 4 is a sectional view on line 4—4 of Fig. 2; and

Fig. 5 is a cross-sectional view of a series of bars illustrating the mode of displacing two bars toward the frame to permit the 25 intermediate bar to be grasped for removal.

Referring to the drawings and to the embodiment of the invention which is selected for exemplification, there is shown a card index comprising a series of cards 6, having 30 their identification-receiving margins arranged in overlapping relationship, although it should be understood that the invention is not limited to an index of this particular class. Each card is held or carried by a 35 card holder, herein comprising a bar 8, having card-attaching means, the latter herein comprising arms 10 conveniently formed of wire presenting pintles 12 suitably hinged to the bar as by slitting and punching the 40 latter to present projections 14 affording recesses 16 best shown in Fig. 4, in which the pintles are received thereby presenting 45 hinges. Suitable provision is made to prevent the pintles from being withdrawn from 50 their places as by providing the bar between the projections 14 with projections 18, herein 55 conveniently formed as tongues projecting laterally from the bar and bent inwardly toward each other until their ends abut, as 60 shown in Fig. 3. These projections may 65 also serve to assist in preventing the bars from riding over one another.

The arms 10 are appropriately secured to 70 their respective cards as by providing said arms with oppositely directed terminal portions 20 received in suitable openings in the

card, the latter for this purpose in the present example being provided with two pairs of slits 22 through which the terminal portion of the wire is threaded, as best shown 60 in Fig. 2. The relative arrangement of the parts is such that the sheet can be detached from the holder only by diminishing the distance between the card-engaging portions of its attaching means, that is to say by reducing the distance between the extremities of the terminal portions 20 to a sufficient extent to allow one of them to be withdrawn from one of the slits 22. This is a distinct 70 advantage, because it prevents the cards from becoming accidentally detached from their holders as they cannot be detached without first removing the holders from the frame now to be described owing to the fact that the bar, while in the panel, cannot 75 be flexed sufficiently to permit of detaching the card therefrom.

The frame herein selected for exemplification comprises a panel formed of a piece of sheet material 24, such as thin sheet metal, having guides, herein Z-bars 26, suitably secured thereto as by soldering or welding and presenting inwardly directed flanges 28 overlying the terminal portions of the bars 8 and affording channels 30 in which the 80 ends of the bars are received, as best shown in Fig. 2. The bars are placed edge to edge in series and preferably have their adjacent 85 edges contacting throughout; they extend transversely of the guides and are slidable 90 lengthwise with the latter.

Removal and replacement of the bars in the present embodiment is accomplished by making them flexible so that they can be bent or bowed sufficiently to reduce their 95 length to a distance less than the space between one overlying flange and the bottom of the channel under the other flange. To this end, each bar is preferably made of a piece of thin tempered steel stock. This 100 bending or bowing of the bar not only permits the latter to be removed from the frame but presents a convenient way of allowing the card to be removed from the holder by bending the bar in the proper direction to 105 cause the extremities 20 of the arms 10 to approach each other and thereby to withdraw one arm from one of the openings in the sheet.

Thus it is apparent that while accidental 110 separation of the card and its holder is impossible, yet one can be detached from the

other instantly by simply first removing the holder from the frame. Rearrangement and reclassification of the index from time to time may be accomplished with ease 5 by removing any card with its holder and reinserting it in a new place, previous to which it is necessary of course to provide a space at the desired point by sliding the adjacent cards and their holders along their 10 guideways in a well-known manner.

The removal of any given holder from its place is facilitated by making provision to permit any two holders to be displaced inwardly in a direction transverse to their 15 normal plane, thereby to render the intermediate holder accessible to be grasped for removal in the manner clearly illustrated in Fig. 5. One convenient way of rendering this possible is by providing the frame 20 with a depression 32 (see Fig. 2) into which the holders may be displaced by simply pressing them inwardly. In the present example the depression is simply a space between a pair of ribs 34 presented by the 25 plate 24, thus elevating the bars an appropriate distance above the front surface of the plate, it being understood of course that the channels 30 are preferably of sufficient 30 depth from front to back to permit the bars to be normally held in their places without stress. When a given bar is to be removed, the two bars on either side of it are pressed inwardly by the thumb and forefinger, as 35 illustrated in Fig. 5, and the intermediate bar is then grasped and bent in an outward direction at its central portion to withdraw its ends from beneath its overlying flanges. The bar can then be detached from the sheet 40 by bending the bar in the opposite direction as before described.

Having thus described one embodiment of the invention but without limiting myself thereto, what I claim and desire by Letters Patent to secure is:

- 45 1. In a file, the combination of a frame, a plurality of cards, and a plurality of card holders held by said frame, each holder comprising a bar and attaching means hinged to said bar and secured to the card held by such holder, each holder being adapted to prevent the card held thereby from being detached from such holder without first detaching the latter from said frame.
- 50 2. In a file, the combination of a frame, a plurality of cards, and a plurality of card holders held by said frame, each holder comprising a bar and attaching means hinged to said bar and secured to the card held by such holder, said holder having provision for detaching the same from its card by diminishing the distance between the card-engaging portions of said attaching means.
- 55 3. In a file, the combination of a frame, a

plurality of cards, and a plurality of card holders held by said frame, each holder comprising a bar and attaching means hinged to said bar and secured to the card held by such holder, said holder having provision for detaching the same from its card by bending the same to diminish the distance between the card-engaging portions of said attaching means. 70

4. In a file, the combination of a frame, a plurality of cards, and a plurality of card holders held by said frame, each holder comprising a bar and attaching means hinged to said bar and secured to the card held by such holder, each card being provided with openings, and its attaching means being received in opposite outward directions into said openings. 75

5. In a file, the combination of a frame, a plurality of cards, and a plurality of card holders held by said frame, each holder comprising a bar and attaching means hinged to said bar and secured to the card held by such holder, each card being provided with openings, and its attaching means having oppositely and outwardly directed portions 80 received in said openings. 85

6. In a file, the combination of a frame, a plurality of cards, and a plurality of card holders held by said frame, each holder comprising a bar and attaching means hinged to said bar and secured to the card held by such holder, each card being provided with openings, and its attaching means comprising arms hinged to such bar and having outwardly directed terminal portions received in said openings. 90 100

7. In a file, the combination of a frame presenting inwardly directed flanges and oppositely disposed channels behind said flanges and a pair of ribs intermediate said channels, said ribs presenting between them a depression, a plurality of cards having free, overlapping margins presented at the front, and a plurality of card holders comprising straight bars abutting edge to edge, having their ends received in said channels and having intermediate portions resting on said ribs, said flanges, said channels, said ribs, and said bars, being cooperatively arranged to permit any given bars to be displaced inwardly in a direction transverse to their normal plane, thereby to permit an intermediate bar to be grasped for removal. 105

110 8. In a file, the combination of a frame presenting inwardly directed flanges and oppositely disposed channels behind said flanges and a pair of ribs intermediate said channels, said ribs presenting between them a depression, a plurality of cards having free, overlapping margins presented at the front, and a plurality of card holders comprising straight bars abutting edge to edge, having their ends received in said channels and having intermediate portions resting on said ribs, said flanges, said channels, said ribs, and said bars, being cooperatively arranged to permit any given bars to be displaced inwardly in a direction transverse to their normal plane, thereby to permit an intermediate bar to be grasped for removal, said channels being greater in depth from front to back than the thickness of said bars, and the height of said ribs being such that the front faces of said bars are held snugly against the rear faces of said flanges, said channels providing spaces to permit the ends of said bars to recede rearwardly when the intermediate portions of said bars are bowed in a forward direction for removal. 115

120 9. In a file, the combination of a frame presenting inwardly directed flanges, oppo- 125

130

sitely disposed channels behind said flanges, and a lengthwise depression intermediate said channels, a plurality of cards having one set of overlapping margins presented at 5 the front, and a plurality of card holders comprising straight bars abutting edge to edge, having their ends received in said channels and having intermediate portions extending across said depression, said 10 flanges, said channels, said depression and said bars, being cooperatively arranged to permit any given bars to be displaced into said depression in a direction transverse to their normal plane, thereby to permit an 15 intermediate bar to be grasped for removal.

9. In a paper file, the combination of a frame, a series of parallel bars held by said frame, a series of sheets having overlapping margins, and means offset from said bars 20 attaching said sheets thereto, said bars and said means having provision to prevent removal of a given sheet from its bar without first removing such bar from said frame.

10. In a paper file, the combination of a frame, a series of bars held by said frame, a series of overlapping sheets, and means interposed between said bars and said sheets 25 attaching them together, said bars and said means having provision to prevent removal 30 of a given sheet from its bar without first removing such bar from said frame.

11. In a paper file, the combination of a frame, a series of bars held by said frame, a series of sheets having overlapping margins, and means laterally disposed with 35 respect to the longitudinal dimensions of said bars for attaching said sheets thereto, said bars and said means having provision to prevent removal of a given sheet from its 40 bar without first removing such bar from said frame.

12. In a paper file, the combination of a frame, a series of bars held by said frame, a series of sheets having overlapping margins, and means holding said sheets spaced 45 from said bars, and attaching said sheets thereto, said bars and said means having provision to prevent removal of a given sheet from its bar without first removing 50 such bar from said frame.

13. In a file, the combination of a frame, a plurality of cards, and a plurality of card holders held by said frame, each holder comprising a bar and attaching means hinged to 55 said bar and secured to the card held by such holder, said attaching means being adapted to prevent a given card from being detached from its holder without first detaching the latter from said frame.

60 14. In a file, the combination of a frame, a plurality of cards, and a plurality of card holders held by said frame, each holder comprising a bar and attaching means hinged to 65 said bar and secured to the card held by such holder, said attaching means being

adapted to prevent a given card from being detached from said attaching means without first detaching said holder from said frame.

15. In a file, the combination of a frame, a plurality of cards, and a plurality of card holders held by said frame, each holder comprising a bar and attaching means hinged to 70 said bar and secured to the card held by such holder, said attaching means being adapted to prevent a given card from being 75 attached to said attaching means without first detaching said holder from said frame.

16. In a file, the combination of a frame, a plurality of cards, and a plurality of card holders held by said frame, each holder comprising a bar and attaching means hinged to 80 said bar and secured to the card held by such holder, said attaching means being adapted to prevent a given card from being 85 attached to or detached from said attaching means without first detaching said holder from said frame.

17. In a file, the combination of a support, a series of overlapping sheets, and a series 90 of parallel bars supported by said support, said bars being adapted to have their normal length diminished, said sheets and said bars having cooperative means attaching said sheets to their respective bars and providing for detachment of said sheets from their 95 respective bars only by diminishing the effective length of said bars.

18. In a file, the combination of a support, a series of parallel bars supported by said support, each bar presenting a pair of aligned bearings extending lengthwise thereof, sheet-attaching means comprising pintles received in said bearings, and a series of sheets associated with said bars, respectively, and attached to said attaching means, each sheet and its attaching means having cooperative provision to prevent detachment of such sheet from its attaching means without first detaching the associated bar from 105 said support.

19. In a file, the combination of a support, a series of parallel bars supported by said support, each bar presenting a pair of aligned bearings extending lengthwise thereof, sheet-attaching means comprising oppositely directed pintles received in said bearings and oppositely directed terminal portions, and a series of sheets associated with 110 said bars, respectively, and provided with openings which receive said attaching means, said terminal portions and said openings cooperating to prevent removal of said sheet from said attaching means without first detaching the associated bar from said support.

20. In a file, the combination of a support, a series of parallel bars attached to said support, said bars being adapted to have their normal length diminished, and a series of sheets, said sheets and said bars having cooperative means attaching said sheets to 125 130

their respective bars and providing for detachment of said sheets from their respective bars only by diminishing the effective length of said bars, and said support and said bars having cooperative means to permit detachment of said bars from said support by diminishing the effective length of said bars.

21. In a paper file, the combination of a support, a series of overlapping sheets presenting openings, and a series of sheet-supporting bars attached to said support and having projections whose free ends are directed toward the adjacent ends of said bars and are received in said openings, respectively, said bars being adapted to have the normal distance between their ends changed, said support and said bars presenting cooperative means permitting said bars to be detached from said support by changing the distance between the ends of each bar.

22. A filing element comprising, in combination, a card presenting openings, and a bendable card-supporting bar presenting projections whose free ends are directed towards the ends of said bar and are received in said openings, respectively, and are removable from said openings by bending said bar to reduce the distance between said projections.

23. A filing element comprising, in combination, a card presenting openings, and a card-supporting bar presenting attaching

means elevated above the surface of said bar and received in said openings, respectively, said bar being bendable to enable the distance between said card-attaching means to be reduced to withdraw the same from said openings.

24. A file comprising, in combination, a support, a series of parallel bars attached to said support, and a series of sheets associated with said bars, respectively, each sheet and its associated bar having cooperative means attaching such sheet to its bar, and providing for the detachment of such sheet from its bar only by removing such bar from said support.

25. In a file, the combination of a support, a series of parallel bars attached to said support, said bars being adapted to have their normal length diminished, and a series of sheets associated with said bars, respectively, each sheet and its associated bar having cooperative means attaching such sheet to its bar, and providing for attachment of such sheet to its bar only by diminishing the effective length of such bar, and said support and said bars having cooperative means to permit attachment of said bars to said support by diminishing the effective length of said bars.

In testimony whereof, I have signed my name to this specification.

JOHN S. SMALL.
